UNITED STATES PATENT OFFICE

LOUIS MELIND, OF CHICAGO, ILLINOIS

STAMP

Application filed April 5, 1930. Serial No. 441,907.

This invention relates to stamping devices, and more particularly to means for identifying the stamping or printing elements of such devices.

5 My invention is particularly adapted for use with hand stamps, though it is capable of being used for other purposes. One of the main objects of my invention is to provide simple and efficient means for identifying 10 stamps, such means being capable of application to a stamp without material alteration in the construction thereof. A further object is to provide means for securing the handle or gripping element of a stamp to the block 15 or equivalent member which carries the stamp proper, such securing means also serving to effectively hold the identifying means in position upon the block of the stamp.

Further objects and advantages of my 20 invention will appear from the detailed description.

In the drawings:

Figure 1 is a sectional view through a stamp having identifying means applied 25 thereto, in accordance with my invention, this view being taken substantially on line 1-1 of Figure 3, the handle being shown partly in elevation;

Figure 2 is a disassembled view of the 30 stamp and the handle, showing the identifying means applied to the block of the stamp;

Figure 3 is an underneath view of the stamp looking at the printing face thereof; and

35 Figure 4 is a detail end view of the cover member for use with the block.

I have illustrated my invention, by way of example, as applied to a stamp which comprises a mounting block 1, conveniently 40 formed of wood, a bed 2 of sponge rubber, or other suitable material, set into the under-face of the block, and a stamping element 3 suitably secured to the bed 2 and bearing suitable characters thereon for printing upon surfaces of articles which it is desired to 45 mark in a suitable manner. The block 3 is provided, at the upper end thereof, with two laterally projecting flanges 4 conveniently formed integrally with the block. This block 50 may readily be produced from a suitable

length of wood, in the nature of a molding, having one face cut out or grooved to provide the recess for reception of bed 2, and being provided at each side with an outwardly projecting rib to form the flanges 4. 55 A length of molding thus formed can readily be cut into suitable lengths to provide blocks similar to the block 1, thus facilitating production of such blocks with a corresponding saving in cost thereof.

Block 1 is bored out from its upper face, centrally thereof, to provide a socket 5 adapted for reception of a reduced stud 6 at the lower end of a suitably shaped handle 7. The stud 6 has a friction fit in the socket 5 for securing the block 1 to the handle. 60 Stamps of this general type are well known in the art and the manner of use thereof need not be illustrated nor described in detail.

It is frequently necessary to use stamps of this general character and which bear different legends, a plurality of such stamps being commonly put together in a suitable rack or other suitable supporting means. 70 The general appearance of these stamps are quite similar and, in many cases, practically identical, so that it is necessary to view carefully a selected stamp before using the same to be certain that this stamp bears the desired marking or legend. This necessity for carefully considering the stamps before using them, is conducive to error, as well as causing appreciable loss of time and inconvenience. It is desirable that the individual 75 stamps be marked for indicating clearly the legends or markings which such stamps are adapted to print or reproduce.

The means for identifying the individual stamps should be readily visible when the stamp is in its normal position of use, and should be capable of being applied to the stamp at small cost and without necessitating any material changes therein.

Referring more particularly to Figure 1, I provide an insert 8 which conforms to the shape of the top or upper face of block 1 which is, in the particular embodiment illustrated, of rectangular shape. This insert may conveniently be formed of cardboard or other suitable material. The insert 8 is con- 95 100

fined between the upper face of block 1 and a cover member 9. This cover member is preferably formed of a suitable transparent material, such as transparent celluloid. Cover 70 member 9 is provided, at each side thereof, with a channel element 10 adapted for reception of flanges 4 of block 1. The cover member is positioned upon the block 1 by being slid onto the same lengthwise thereof, with the channel 75 elements 10 engaging about and beneath the flanges 4 and coacting therewith to hold the cover member against movement away from the block. The cover member, when thus positioned upon the block, serves to hold the 80 insert 8 in proper position upon the upper face of the block.

The insert 8 bears upon its upper face suitable markings or characters for identifying the stamp with which such insert is associated. Preferably, the identifying data 85 upon the insert corresponds to the printing element 3 of the stamp. The identifying data upon the insert 8 is readily visible through the transparent cover member 9 and the insert is so disposed that the arrangement 90 of the data thereon corresponds to the arrangement of the corresponding printing element of the stamp. The insert thus serves not only to identify the stamp but also to indicate whether the stamp is being held properly for printing the desired legend upon an article in proper relation thereto. Marking the stamping device in this manner is highly advantageous as rendering it possible 95 to ascertain at a glance the particular stamp desired and, also, to determine whether the stamp is being held in proper position for printing therewith upon an article in proper relation thereto.

100 The insert 8 and the cover member 9 are provided with aligned openings which are disposed in register with each other and with socket 5 of block 1. Stud 6 passes through these openings of the insert and the cover member, and serves to effectively secure them 105 against movement relative to each other and to the block 1. When the handle 7 is detached from block 1 for placing the stamp and handle in a kit which may be provided for this purpose, the insert 8 is retained in position 110 upon the block 1 and in proper relation thereto by the cover member 9. Under ordinary conditions, however, the handle 7 will remain in position and secured to block 1, as in Figure 1 of the drawings.

The cover member 9 is preferably made of transparent material, as above stated. This is not essential, however, and the cover member may be made of any suitable material 115 rendered transparent for a sufficient portion of its area to enable the data on the insert 8 to be viewed readily. Obviously, if the cover member be formed of opaque material, the desired results can be accomplished by 120 removing or cutting away suitable portions 125 of the cover member. Preferably the cover member and the insert are disposed upon the top or upper face of block 1. This is not essential, however, and my invention comprehends, in its broader aspects, any other suitable or preferred arrangement of the cover member and the insert. In its preferred and more specific form, my invention utilizes the means for securing the handle to the block for also securing the insert and the cover 130 member against movement relative to each other and the block, though this is not essential in all instances and in many cases the cover member may be relied upon for holding the insert in position.

What I claim is:

1. In a stamping device of the character described, comprising a mounting block and stamping means carried thereby, said block being provided with laterally projecting flanges at its upper end, a cover member fitting upon the upper end of the block and provided with channel elements engaging about said flanges and holding the cover member against movement away from the block, an insert between the cover member and the block and bearing identifying data visible through said member, a handle, and means for securing the handle to the block, said securing means including an element passing through the cover member and the insert and holding them against sliding movement relative to each other and to the block.

2. In a stamping device of the character described, comprising a mounting block and stamping means carried thereby, said block being provided at opposite edges of one face thereof with outwardly projecting flanges, a cover member provided with channel elements slidably engaging over and about said flanges and holding the cover member against movement away from the block, and an insert disposed between the cover member and the block and bearing identifying data for identifying the stamp with which such insert is associated.

3. In a stamping device of the character described, comprising a mounting block and stamping means carried thereby, said block being provided with laterally projecting flanges at its upper end, a cover member fitting upon the upper end of the block and provided with channel elements engaging about said flanges and holding the cover member against movement away from the block, an insert between the cover member and the block and bearing identifying data visible through said member, the cover member and the insert having registering openings and the block being provided with a socket aligned with said openings, and a handle provided with an element extending through the openings of the cover member and the insert and fitting into said socket.

4. In combination, a mounting block and stamping means carried thereby, said block being provided with lateral flanges at its upper end, a transparent cover member fitting upon the upper end of the block and having upon the upper end of the block and having its edge portions formed to provide channel elements engaging about and beneath said flanges and cooperating therewith for holding the cover member against movement away from the block, and an insert between the cover member and the block and bearing identifying data visible through said member.

In witness whereof, I hereunto subscribe my name this 3rd day of April, 1930.

LOUIS MELIND.
